United States Patent

Des. 237,227
Patented Oct. 21, 1975

237,227

CHAIR

George Mergenov, Closter, N.J., assignor to Mohasco Industries Inc., Amsterdam, N.Y.

Filed May 2, 1974, Ser. No. 466,435

Term of patent 14 years

Int. Cl. D6—01

U.S. Cl. D6—37

The figure is a perspective view of a chair illustrating my new design.

The back of the chair is conventionally plain while the side not shown is substantially identical to the side shown.

I claim:

The ornamental design for a chair, as shown and described.
